CLAIM

The ornamental design for a bottle cap, as shown and described.

DESCRIPTION

FIG. 1 is a perspective view of a bottle cap showing our new design;

FIG. 2 is a rear elevation thereof;

FIG. 3 is a front elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is another perspective view of the bottle cap of FIG. 1 showing the band at the base rotated to the locked position;

FIG. 9 is a perspective view of the bottle cap of FIG. 1 shown in a position of use attached to a bottle drawn in broken lines; and,

FIG. 10 is a reference view of the perspective view of the bottle cap shown in FIG. 1 without broken lines therein.

The broken lines depict environmental structure that forms no part of the claimed design.
